UNITED STATES PATENT OFFICE.

AUGUST B. BECK, OF JERSEY CITY, NEW JERSEY.

GIRDLE.

1,401,860.

Specification of Letters Patent. Patented Dec. 27, 1921.

Application filed March 7, 1921. Serial No. 450,410.

To all whom it may concern:

Be it known that I, AUGUST B. BECK, a citizen of the United States, residing at Jersey City, in the county of Hudson and State of New Jersey, have invented certain new and useful Improvements in Girdles; and I do declare the following to be a full, clear, and exact description of the invention, such as will enable others skilled in the art 10 to which it appertains, to make and use the same.

My invention relates to improvements in ladies' girdles of the type employing an elastic belt which usually carries hose supporters, and the principal object of my invention is to associate a relatively narrow strap, such as a silk or satin ribbon, with the elastic belt in such a manner as to allow the user to restrict the waistline, independently 15 of the action of the elastic belt.

In carrying out the above end, a further object is to provide a girdle composed of upper and lower elastic bands connected by a plurality of separate inelastic strips between which the above mentioned strap or ribbon is laced. By this provision, not only is the ribbon or the like properly guided and held in place, but the inelastic strips will not under any circumstances become of 25 greater height than the width of the ribbon, with the result that much better results are obtained than could be had if the belt structure were elastic throughout.

Yet another object is to provide a novel 30 construction which prevents the usual corset fasteners which are used from coming in contact either with the body or the apparel of the user.

With the foregoing in view, the invention 40 resides in the novel construction and association of parts hereinafter described and claimed, the descriptive matter being supplemented by the accompanying drawings.

Figure 1 is a perspective view partly 45 broken away and in section, showing a girdle constructed in accordance with my invention.

Fig. 2 is a detail horizontal sectional view as indicated by line 2-2 of Fig. 1.

50 Fig. 3 is a detail vertical sectional view as designated by line 3-3 of Fig. 1.

In carrying out my invention, I employ a relatively wide elastic belt divided down its front and provided at its meeting ends 55 with reinforcing strips 1 and 2 which carry

the front hose supporters 3, similar supporters 4 being connected in any suitable way with the back portion of the belt. Associated with the belt and extending from end to end thereof, is a relatively narrow inelastic strap 5, such as a silk or satin ribbon, the ends of this ribbon or the like being adapted to be connected to each other, preferably by tying as indicated at 6 in Fig. 2. It will thus be seen that the waist-line may 60 be restricted regardless of the elastic action of the belt.

In the preferred form of construction, the belt is composed of upper and lower elastic bands 7 and 8 respectively, which are 70 spaced apart vertically and connected at their adjacent edges by a plurality of inelastic strips 9 which are disposed edge to edge and stitched at 10 to the band. Each of the strips 9 may well be composed of two lengths 75 of ordinary corset stay covering, stitched together as indicated at 11. It will be understood however that this construction need not be followed in all cases.

The slight spaces existing between the 80 disconnected edges of the vertical strips 9, constitute a plurality of vertical slots 12 through which the strap or the like 5 is passed. The ends of this strap preferably pass beneath the reinforcing strips 1 and 2, 85 and are tied together before said strips are connected, whereby the knot 6 is hidden from view when the belt is completely applied.

Each of the reinforcing strips 1 and 2 is 90 preferably formed of a sheet of fabric folded upon itself to provide two plies which are stitched at their free edges to the band 8 as indicated at 13. A stay 14 is positioned between the plies of the reinforcing 95 strip 2 and carries well known headed studs 15 which project forwardly beyond said strip 2. Between the plies of the reinforcing strip 1 and spaced inwardly from the folding line 16 of said strip, is another stay 17 having metal eyes 18 which project through the inner ply for co-action with the headed studs 15. The portion of the strip 1 between the stay 17 and the folding line 16 constitutes a flap 19 adapted to 100 cover the fasteners 15 and 18 to prevent them from injuring the user's clothing and it will be seen that since the carrying stays 14 and 17 for these fasteners, are located between the inner and outer plies of the rein- 110

forcing strips 1 and 2, they cannot touch the flesh, even if the girdle is worn directly against the skin.

The stays 14 and 17 strengthen the front portion of the girdle to the desired extent, but in most instances, the back portion of the belt is preferably provided with two stays 20 which extend across the bands 7 and 8 and two of the connecting strips 9.

Attention may here be directed to the fact that the bands 7 and 8 are relatively narrow and wide respectively, and if desired, in manufacturing the girdle, the band 8 may be formed by stitching two strips 8^a together on the line 8^b (see Fig. 1). By this construction, it is only necessary to carry in stock one width of elastic for the formation of the bands 7 and 8, one width of such elastic sufficing for the band 7, while two widths are secured together for the band 8. I wish it understood that while this detail of construction may be followed if desired, it is not essential.

The device constructed as or substantially as shown and described, may be easily and inexpensively manufactured and marketed, yet will be highly efficient and in every way desirable, particular attention being directed to the fact that the waistline may be restricted to any desired extent, regardless of the elastic action of the belt. The elasticity of this belt above and below the strap 5, however, will gracefully merge the restricted waistline into the adjacent portions of the figure as will be readily understood. The manner of forming the flap 19 to protect the clothing against the fasteners 15 and 18 is also considered a rather important feature of the invention.

Since excellent results have been obtained from the several details shown and described, these details may be followed if desired. I wish it understood however that within the scope of the invention as claimed, numerous changes may be made.

I claim:

1. A girdle comprising a relatively wide

elastic belt having connecting means at its ends, and a relatively narrow inelastic strap connected with said belt intermediate the edges of the latter and extending from end to end thereof, said strap being adapted to have its ends connected to each other to restrict the waistline independently of the elasticity of the belt. 50

2. A girdle comprising a relatively wide elastic belt having connecting means at its ends and provided intermediate its edges with circumferentially spaced vertical slots, and a relatively narrow inelastic strap passed through said slots and adapted to have its ends connected to each other to restrict the waistline independently of the elasticity of the belt. 60

3. A girdle comprising a relatively wide belt formed of upper and lower bands of elastic material and a plurality of separate inelastic strips disposed edge to edge and connecting said bands in vertical spaced relation, and a relatively inelastic strap laced through the spaces between said strips and passing alternately in front of and behind said strips, the ends of said strap being adapted for connection with each other for the purpose specified. 70

4. A supporter comprising a body encircling portion divided at its front and provided with reinforcing strips along its edges, one of said strips being formed of two plies of fabric united with each other at the edge 80 and having their other edges secured to the supporter, the inner ply having vertically spaced slots spaced inwardly from said united edges, a stay between said plies having eyes passing outwardly through said slits, and fasteners on the other reinforcing strip coöperable with said eyes, the portion of said one reinforcing strip between said stay and said united edges forming a covering flap for said fasteners and eyes when 90 engaged. 85

In testimony whereof I have hereunto set my hand.

AUGUST B. BECK.
